UNITED STATES PATENT OFFICE.

JAMES V. MARTIN, OF ELYRIA, OHIO.

AEROFOIL.

1,400,177.

Specification of Letters Patent. Patented Dec. 13, 1921.

Application filed November 30, 1917. Serial No. 204,602.

To all whom it may concern:

Be it known that I, JAMES V. MARTIN, a citizen of the United States, and resident of Elyria, in the county of Lorain and State of Ohio, have invented certain new and useful Improvements in Aerofoils, of which the following is a specification.

The invention relates to an aerofoil for use on any type of aeroplane construction. 10 It is to be understood that the term aerofoil used herein is of sufficient breadth to include any body projected through the atmosphere for an aerodynamic reaction.

The primary object of the invention is to 15 provide a form of aerofoil which will have a maximum K_y , or lift, and a minimum K_x , or drift coefficient, or a maximum lift-drift ratio at one angle of incidence and which has a relatively slow rate of change from said 20 maximum lift-drift ratio when the aerofoil is moved from said angle of incidence.

I attain this object broadly by providing 25 an aerofoil of a double convex form with its longitudinal chord extending from the leading to the rear edges, disposed within the outlines of the aerofoil and with its longest ordinate intersecting the chord approximately at the center of pressure of the aerofoil.

30 Another object of the invention is to provide an aerofoil which can be braced internally to withstand the strains incidental to high pressures thus eliminating practically all external bracing.

35 A still further object of the invention is to provide a type of aerofoil which will minimize interference from a superimposed aerofoil and which will tend to preserve a relatively high lift to drift ratio in the presence 40 of any superimposed aerofoil.

Various other objects and advantages of the invention will be in part obvious from an inspection of the accompanying drawings and in part will be more fully set forth in 45 the following particular description of one form of structure embodying my invention, and the invention also consists in certain new and novel features of construction and combination of parts hereinafter set forth 50 and claimed.

In the accompanying drawings:

Figure 1 is a plan view looking down upon one of the aerofoils shown in section in Figs. 3 to 6 and illustrating a preferred embodiment of my invention.

Fig. 2 is a vertical sectional view taken

longitudinally of the aerofoil and on the line 2-2 of Fig. 1, and showing the upper plane of a biplane machine;

Figs. 3 to 6 inclusive are transverse sectional views, any one of which may be regarded as taken on the line 3-3 of Fig. 1;

Fig. 7 is a transverse sectional view through the main wing beam; and

Fig. 8 is a diagrammatic view showing 65 the plotting for the upper profile in Figs. 3 to 6 inclusive.

This aerofoil when considered in plan as shown in Fig. 1 is relatively wide across the line of flight compared with its length in the direction of its line of flight. The front or leading edge is defined by a leading edge bar 10 disposed parallel to the rear or trailing edge defined by a rear edge bar 11. Opposite side edges 12 recede from the front 75 toward the rear edge as shown in Fig. 1.

Referring to any of the forms shown in Figs. 3 to 6, it is seen that the aerofoil includes an upper skin surface 13 and a corresponding lower skin surface 14, curving in 80 a general double convex curve from the leading edge 10 to the rear of trailing edge 11.

The curvature of these surfaces is of prime importance in this disclosure. For the purpose of establishing points of reference for 85 these curves, it is to be considered that vertical sections taken through the aerofoil from front to rear are of the general form shown in these figures. The aerofoil is so positioned that its longitudinal chord or center 90 line indicated by the dotted line 15 extends from the leading to the rear edge and is contained entirely within the outlines of the aerofoil. The surfaces are symmetrically positioned with reference to the chords, that 95 is, the longest ordinate on one side is in line with the longest ordinate on the other side of the chord, and correspondingly the correlated ordinates across the chord decrease in the same ratio toward ends of the chord. 100

The surfaces are so disposed that the greatest thickness of the aerofoil is approximately one-third of the length of the chord spaced from the leading edge 10. This portion of greatest thickness is preferably positioned at the center of pressure on the aerofoil, herein indicated by the lines *cp*. By this arrangement it is possible to dispose the greatest amount of internal trussing at the point on the aerofoil which is subjected to 110 the greatest distorsional strains.

For the purpose of defining mathemati-

cally one preferred form of curve for the upper profile at 13 in Figs. 3-6, reference is made to the resultant curve found in Fig. 8 which may be plotted as follows:

- 5 Draw upper half of parabola VCE, whose equation is $y^2 = .187KX$, about the axis X—X, where K is a constant equal to the chord of the aerofoil selected.

Draw axis Y—Y normal to X—X at V.

- 10 Draw axis A—A at an angle of 20° to X—X, intercepting it at a distance —.238 K from Y—Y.

Erect a perpendicular to X—X at B, a distance of .061K from Y—Y.

- 15 Through the intersection of this line with A—A draw a line O—O normal to A—A.

Erect ten perpendiculars to A—A, a distance of .1K apart with the first perpendicular spaced from O—O a distance of .1K.

- 20 Draw H—H normal to A—A, a distance of .0074K from O—O.

Draw J—J normal to A—A, a distance of —.0015K from 10—10.

- 25 Draw CC' normal to X—X at C', a distance of .622K from Y—Y, intercepting 6—6 and parabola VCE at C.

Draw the arc of a circle R_1 , (whose equation is $x^2 + y^2 = .00005476K^2$, referred to the coördinate axes A—A and H—H) beginning on axis A—A and terminating at the parabola VCE. This circle will be osculatory to O—O and VCE. This will be the first part of the upper profile.

- 30 The arc of the parabola VCE, (whose equation is $y^2 = .187KX$ referred to axes X—X and Y—Y), included between the lines H—H and 6—6 will be the second part of the profile.

At point C on 6—6 draw a tangent (whose equation is $Y = K (.038X + .191)$, referred to the coördinate axes X—X and Y—Y), to the parabola VCE, and terminating at J—J. The straight line included between 6—6 and J—J is the third part of the profile.

- 45 Draw the arc of a circle R^2 , (whose equation is $X^2 + Y^2 = .00000225K^2$, referred to coördinate axes A—A and J—J), beginning at the tangent CR₂ and terminating on axis A—A. This circle will be osculatory to CR₂ and 10—10. This is the fourth and final part of the profile.

The curve so formed will respond to the upper curve of the aerofoils shown in Figs. 5 to 6 inclusive and also, when reversed, to the lower curve of the aerofoil shown in Fig. 3. The lower profile of the form shown in Fig. 4 is a locus whose ordinates are three-fourths of the ordinates of the upper profile. The lower profile of the form shown in Fig. 5 is a locus whose ordinates are one-half of the ordinates of the upper profile and similarly the profile of the form shown in Fig. 6 is a locus whose ordinates are one-fourth of the ordinates of the upper profile.

65 As shown in Fig. 1 the aerofoil includes an

internal framework formed of a plurality of wing bars in addition to the leading and trailing edge bars 10 and 11. These wing bars extend lengthwise in parallel relation and are spaced across the width of the aerofoil. The internal wing bars include a main wing bar 16 and a rear wing bar 17. The wing bars are box-formed structures combining lightness with strength.

As shown in Fig. 7, the wing bars are 75 formed of two stress boards, an upper tension board 18 and a lower compression board 19 with an upstanding web board 20 extending therebetween and fitted into the top and bottom boards to form in effect an I beam 80 construction. Filler blocks 21 are positioned on opposite sides of the web board and between the flanges formed by the extensions of the stress boards 18 and 19 on opposite sides of the web board. If desired the main 85 wing bar may be additionally strengthened by fastening metal plates 22 to opposite sides of the web board. A plurality of transversely spaced and longitudinally extending ribs 23 are positioned edgewise between the 90 leading and trailing edge bars and normal to the wing bars. These ribs give the aerofoil the profile shown in Figs. 3 to 6. Certain of the ribs 24 are enlarged and strengthened sufficient to act as struts, and all of the 95 ribs have a depth sufficient to permit the wing bars to be passed therethrough as shown in Fig. 2. Pairs of diagonal straps 25, preferably piano wires, are stretched between adjacent struts and coat therewith 100 to take up the drift stresses on the aerofoil when the plane is in motion. One end of each of the straps is attached to the lower portion of one of the struts adjacent the leading edge bar and the other end is attached to the upper portion of the next adjacent strut at the conjunction of this next strut with the rear wing bar.

While I have shown and described, and have pointed out in the annexed claims, certain novel features of my invention, it will be understood that various omissions, substitutions and changes in the form and details of the device illustrated and in its operation may be made by those skilled in the 115 art without departing from the spirit of the invention.

Having thus described my invention, I claim:-

1. A double convex aerofoil with a considerable part of the central portion of its normal upper and lower surface forming parabolic curves, the chord of said curves extending in the general direction of flight of the aerofoil, the parabolic curve formed 120 by the central portion of upper surface being of the form approximating the curve indicated by the formula $y^2 = .187KX$ where K is a constant equal to the chord of the aerofoil.

2. A double convex aerofoil having its chord extending approximately in the line of flight of the aerofoil and positioned between the normal upper and lower surfaces thereof, the upper and lower surfaces being symmetrially curved relative to each other from the leading to the trailing edges, and a considerable part of the central portion being parabolic and of the class having the formula $y^2=0.187KX$, where K is a constant equal to the chord of the aerofoil.

3. A double convex aerofoil having its chord extending approximately in the line of flight of the aerofoil and positioned between the normal upper and lower surfaces thereof, the upper and lower surfaces being each of the same species of curvature relative to each other from the leading to the trailing edge, the surfaces being so positioned that the ordinates below the chord are fractional parts of the corresponding ordinates above the chord, the ratio between the parts of certain ordinates above the chord and the corresponding parts below the chord being the same for a plurality of the ordinates spaced a material distance along the length of the chord.

4. An aerofoil having a profile, the major portion of which is parabolic and of the class having the formula $y^2=0.187KX$, where K is a constant equal to the chord of the aerofoil.

5. An aerofoil having a profile, the major portion of which is parabolic and of the class having the formula $y^2=0.187KX$, where K is a constant equal to the chord of the aerofoil, and another portion of which is a tangent osculatory to the parabolic portion.

6. An aerofoil having a profile, the major portion of which is parabolic and of the class having the formula $y^2=0.187KX$, where K is a constant equal to the chord of the aerofoil, and another portion of which is a tangent, whose equation is $y=K(0.038X-0.191)$ osculatory to the parabolic portion.

7. An aerofoil construction having a profile the central portion of which is parabolic, an adjacent portion flat and osculatory to the parabolic portion and a third portion circular and osculatory to one of the other portions.

8. An aerofoil construction having a profile on one side of the chord formed in order from front to rear of a circular portion, a parabolic portion, a flat portion and a circular portion.

9. An aerofoil construction having a profile on one side of the chord formed in order from front to rear of a circular portion, a parabolic portion, a flat portion and a circular portion, and having a profile on the other

side of the chord with the same relative order of parts.

10. A double convex aerofoil having its chord intersecting the leading and trailing edges, the surfaces being so positioned that the length of the part of each ordinate below the chord is less than the length of the part thereof above the chord and the ratio between said lengths of any one ordinate being substantially the same for all other ordinates along a material length of the chord.

11. A double convex aerofoil with its chord contained within the upper and lower surfaces, said surfaces being spaced from the chord with the longest ordinate on one side of said chord being in line with the longest ordinate on the other side of the chord, the correlated ordinates across the chord decreasing in the same ratio toward one end of the chord, the lower ordinates in each case being of less length than the corresponding upper ordinate whereby there will be a greater thickness of aerofoil part above the chord than below the chord.

12. A double convex aerofoil with its chord contained within the upper and lower surfaces, said surfaces being spaced from the chord with the longest ordinate on one side of said chord being in line with the longest ordinate on the other side of the chord and positioned above one-third of the length of the chord from the leading edges, the correlated ordinates across the chord decreasing in the same ratio toward one end of the chord, the lower ordinates in each case being of less length than the corresponding upper ordinate whereby there will be a greater thickness of aerofoil part above the chord than below the chord.

13. A double convex aerofoil having relatively sharp leading and trailing edges and with its chord intersecting said edges, the length of the part of each ordinate below the chord being approximately one-fourth of the length of the corresponding part above the chord.

14. A double convex aerofoil having its chord contained between the upper and lower surfaces, the profile of the major portion of both of said surfaces being parabolic, the length of the parts of the ordinates below the chord being each a fractional part of the length of the parts of the corresponding ordinate above the chord, said fractional part being substantially the same for the ordinates along a considerable part of the chord.

Signed at New York in the county of New York and State of New York this 17th day of August, A. D. 1917.

JAMES V. MARTIN.

DISCLAIMER

1,400,177.—*James V. Martin*, Elyria, Ohio. AEROFOIL. Patent dated December 13, 1921. Disclaimer filed February 26, 1937, by the patentee.

Hereby enters this disclaimer to the following words appearing at page 1, lines 8 to 13 of the specification which your petitioner desires to erase from said specification:

“The invention relates to an aerofoil for use on any type of aeroplane construction. It is to be understood that the term aerofoil used herein is of sufficient breadth to include any body projected through the atmosphere for an aero-dynamic reaction.” and hereby disclaims the invention set out in claims 1 to 14 of said patent except when the aerofoil is the wing of an aeroplane.
